UNITED STATES PATENT OFFICE.

JAMES G. BLUNT, OF SCHENECTADY, NEW YORK.

LATERAL-MOTION DEVICE FOR LOCOMOTIVE DRIVING BOXES.

Application filed January 22, 1925. Serial No. 2,958.

To all whom it may concern:

Be it known that I, JAMES G. BLUNT, a citizen of the United States, residing at Schenectady, Schenectady County, New York, have invented a new and useful Improvement in Lateral-Motion Devices for Locomotive Driving Boxes, of which the following is a specification, reference being had to the accompanying drawings, in 10 which—

Fig. 1 is a plan, partly in section, showing the application of my invention to the driving axle boxes of a locomotive engine; Fig. 2 is a front elevation thereof partly in 15 section; Fig. 3 is a side elevation thereof; and Fig. 4 is a detailed perspective of one of the rockers.

My invention relates to devices for controlling the lateral motion of driving axle boxes of locomotive engines and thereby limiting the lateral movement of the driving axles, and at the same time providing resistance to that movement to aid the locomotive in absorbing lateral shocks and to assist it in passing around curves. My improved device is so designed that the lateral movement of one driving box is transmitted to the opposite frame, with the result that the reaction of the device against the frame housing the opposing box serves to exert pressure upon the box with which the movement initiated and thus tends to restore it to normal position. My invention, while contemplated for use on two-cylinder locomotives, is particularly applicable to three-cylinder and Mallet types of locomotives, which have obstructing mechanism between the frames, since it offers resistance to lateral movement without disturbing or changing the normal distribution of weight on the bearing journals. My invention also comprises the various features which I shall hereinafter describe and claim.

Referring to the drawings, in each side 45 of the main frame 1, driving axles 2 are journalled in axle or driving boxes 3, working in pedestals 1^a in the frame 1, and guided by wedges 4 and shoes or journals 5. Bearing on the boxes 3 are saddles 7, to 50 which the load is transmitted through the springs 6^a, from the spring hangers 6.

Extending along the top of each side member of the frame 1 and across a pedestal 1^a is a rocker shaft bearing bracket 8. Transversely disposed bolts 9, extending 55 horizontally in the direction of the stress,

secure each bracket 8 to the frame, and by means of the nuts 9^a, which bear against the inner faces of the frame, and of the nuts 9^b, which bear against the inner faces of the brackets 8, take up part of the stresses imposed upon the webs 8^a of the brackets 8. In the ends of the brackets 8, journals 8^b are formed for reception of the rocker shafts 10, which are of a length to allow them to 60 protrude through the bearings 8^b for the application of the cotter pins 11 by which the shafts 10 are held in position. The rock shafts 10 also form fulcrums for the forked rocking levers 12 which at their lower ends 70 straddle the axle 2 and carry rollers 13, mounted in the jaws 12^a, which bear against the inside faces of the boxes 3 and so provide a rolling bearing against the boxes 75 3 as they rise and fall relative to the frame 2. The lower ends of the levers 12 also have lugs 12^b, which bear on the inner faces of the frame members 1 and thus prevent outward movement of the lower ends of the levers. The levers 12 have hubs 12^c to provide 80 ample bearing surfaces on the rock shafts 10. The limbs of the levers 12 converge and unite near their upper ends and have upward extensions containing twin concave bearings 12^d for engagement with the lateral motion resistance device 14.

The device 14 comprises a yoke 14^a in which are disposed spring elements 15 of the required capacity bearing at one end against one end of the yoke and at the other against 85 a spring seat 16. A headed bolt 17 seats in a central aperture in the seat 16, passes through the spring elements 15, an end of the yoke 14, and carries at its opposite end a winged bearing 18. The bearing 18 90 and the end 14^b of the yoke have inwardly facing convex faces which are engaged by the concave bearings 12^d of the levers 12. Any desired amount of tension may be 95 procured by inserting into the yoke, spring elements of the proper capacity, and by regulating the position of the nut 19 upon the bolt 17.

When my improved device is in operation, if one of the driving boxes is displaced inwardly to the extent of the clearance permitted by the space A between the flanges of the boxes 3 and the pedestal guides, as is shown in Fig. 1, the inward movement of the box will cause the lower end of the 105 lever 12 on that side of the engine also to move inwardly, thereby causing the upper 110

end of the lever to move outwardly because of the rotation of the lever upon the rock shaft 10. As the lever 12 is connected to the opposite lever 12 through the spring resistance device 14 the movement of the upper end of one lever tends to move the other lever correspondingly, but such movement of the other lever is prevented since the projection 12^b at the lower end bears against the frame. Hence compression of the springs 15 takes place which sets up a force tending to return to its normal position the box from which the movements just described initiated.

My invention is of particular advantage, since it does not require any particular construction of frame or driving box but may be applied to driving boxes of the usual character. It has the further advantage that in removing driving axles from the locomotive no part of the mechanism requires removal or disturbance.

The terms and expressions which I have employed are used as terms of description and not of limitation, and I have no intention, in the use of such terms and expressions, of excluding any mechanical equivalents of the feature shown and described, or portions thereof, but recognize that various structural modifications are possible within the scope of the invention claimed.

What I claim is:

1. In a locomotive engine, the combination of a frame; driving axle boxes mounted in said frame and capable of a limited lateral movement relative thereto; an axle rotating in said boxes; and mechanism supported by the frame comprising means for transmitting lateral movement of one box to bring pressure upon the portion of the frame housing the opposite box and of reacting against the first mentioned box to exert pressure to restore it to normal position.
2. In a locomotive engine, the combination of a frame; driving axle boxes mounted in said frame and capable of a limited lateral movement relative thereto; a lateral resistance device; and a connection between said device and each driving box supported by the frame, said device comprising means for transmitting movement of one box to bring pressure upon the portion of the frame housing the opposite box, said device also comprising means for exerting pressure to restore the first mentioned box to normal position.
3. In a locomotive engine, the combination of a frame; driving axle boxes mounted in said frame and capable of a limited lateral movement relative thereto; a lateral resistance device, and levers pivoted upon the frame engaging the lateral resistance device and the boxes, said lateral resistance device

and said levers comprising means for transmitting lateral movement of one box while forming a fulcrum against the frame on the opposite side, and at the same time forming a resistance to lateral movement of either box independently of the other and constantly tending to move the resisting box back into normal position.

4. In a locomotive engine, the combination of a frame; driving axle boxes mounted in said frame and capable of a limited lateral movement relative thereto; a lateral resistance device; levers pivoted upon the frame and engaging the lateral resistance device and the boxes; said lateral resistance device and said levers comprising means for resisting the lateral movement of one box while forming a fulcrum against the frame on the opposite side and constantly tending to move the box offering resistance back into normal position; and means for limiting the outward movement of the free ends of said levers.

5. In a locomotive engine, the combination of a frame; driving axle boxes mounted in said frame and capable of a limited lateral movement relative thereto; levers pivoted upon said frame; and spring mechanism joining ends of said levers, the opposite ends of said levers having a bearing upon said frame, the levers and spring mechanism comprising means for transmitting lateral motion of either box in the form of pressure against the opposite frame and of reacting against the said box to restore it to normal position.

6. In a locomotive engine, the combination of a frame; driving axle boxes mounted in said frame and capable of a limited lateral movement relative thereto; forked levers mounted in pivot bearings rigid with said frame; rollers on said levers engaging said boxes; and spring elements engaged by said levers, said spring elements being disposed so as to resist the movements of the levers upon rotation thereof caused by the inward movement of said boxes.

7. In a locomotive engine, the combination of a frame; driving axle boxes mounted in said frame and capable of vertical and lateral movement relative to said frame; levers of inverted V-shape mounted in pivot bearings rigid with said frame; rollers on the V engaging said boxes and capable of vertical movement relative thereto; and spring elements engaged by the closed end of the V, said spring elements being disposed so as to resist the movement of the closed ends of the levers upon rotation of such levers caused by the inward movement of said boxes.

JAMES G. BLUNT.
